UNITED STATES PATENT OFFICE.

IRA M. CLARKE, OF PITTSBURGH, PENNSYLVANIA, ASSIGNOR TO JOHN B. HIGBEE
GLASS COMPANY, OF BRIDGEVILLE, PENNSYLVANIA, A CORPORATION OF PENN-
SYLVANIA.

DESIGN FOR A PRESSED-GLASS VESSEL.

44,629.

Specification for Design.

Patented Sept. 9, 1913.

Application filed June 4, 1913. Serial No. 771,770. Term of patent 3½ years.

To all whom it may concern:

Be it known that I, IRA M. CLARKE, a citizen of the United States of America, and residing in the city of Pittsburgh, county of Allegheny, and State of Pennsylvania, have invented a new, original, and ornamental Design for a Pressed-Glass Vessel, of which the following is a specification, reference being had to the accompanying drawing, forming a part thereof.

Figure 1 is a plan view of a vessel embodying my design and Fig. 2 is a perspective thereof.

I claim:

The ornamental design for pressed glass vessel, as shown.

IRA M. CLARKE.

Witnesses:

EDW. A. LAURENCE,
JOHN MCKELVIE.
